US00D797917S

(12) **United States Design Patent** (10) Patent No.: **US D797,917 S**
(45) Date of Patent: **** Sep. 19, 2017**

(54) **FAN WITH LIGHT**(71) Applicant: **DELTA T CORPORATION**,
Lexington, KY (US)(72) Inventors: **Richard Oleson**, Lexington, KY (US);
Jason Williams, Wilmore, KY (US)(73) Assignee: **DELTA T CORPORATION**,
Lexington, KY (US)(**) Term: **15 Years**(21) Appl. No.: **29/536,481**(22) Filed: **Aug. 17, 2015**(51) LOC (10) Cl. **14-02**

(52) U.S. Cl.

(57) **CLAIM**

The ornamental design for a fan with light, as shown and
described.

DESCRIPTION

FIG. 1 is a bottom perspective view of the invention;

FIG. 2 is a top perspective view of the invention;

FIG. 3 is a front view of the invention;

FIG. 4 is a right side view of the invention;

FIG. 5 is a rear view of the invention;

FIG. 6 is a left side view of the invention;

FIG. 7 is a top view of the invention; and,

FIG. 8 is a bottom view of the invention.

The broken lines represent portions of the structure that
forms no part of the claim.

1 Claim, 8 Drawing Sheets
